LUMINAIRE

Martin L. Lasker, Flushing, N.Y., assignor to McPhilben
Manufacturing Co., Inc., Brooklyn, N.Y., a corporation of New York

Filed Feb. 1, 1960, Ser. No. 59,213

Term of patent 14 years

(Cl. D48—23)

FIG. 4

Fig. 1 is a perspective view of a luminaire showing my new design;

Fig. 2 is a side elevational view thereof;

Fig. 3 is a bottom plan view thereof; and

Fig. 4 is an elevational view thereof as seen from the opposite end of Fig. 1.

I claim:

The ornamental design for a luminaire, as shown.
